DENTIFRICE AND TOOTHBRUSH CONTAINER

Percy Gordon Watt, Palmerston, Ontario, Canada

Application January 28, 1943, Serial No. 474,050

2 Claims. (Cl. 206—15.1)

The invention relates to dentifrice and toothbrush containers as pointed out in the accompanying specification and illustrated in the drawings which forms a part of the same.

The invention consists essentially of the novel features of construction as pointed out broadly and specifically in the claims for novelty following a description containing an explanation in detail of an acceptable form of the invention.

The objects of the invention are to furnish a dentifrice and toothbrush container which shall be light in weight, cheap to manufacture, of simple and sturdy design, to furnish a dentifrice and toothbrush container which may easily be carried in ladies' hand bags or on the pockets of suits in the manner of a fountain pen, to provide a dentifrice and toothbrush container which shall be suitable for carrying tooth paste and toothbrush in an integral container or which may be used for carrying tooth powder and toothbrush in one container having few parts entirely detachable thus making it practically impossible for the user to lose either tube or cap therefor or the brush itself.

In the drawing:

Figure 1 is an elevational view of the dentifrice and toothbrush container.

Figure 2 is a vertical sectional view of the dentifrice and toothbrush container on the line 2—2 in Figure 1.

Figure 3 is a fragmentary view of lower part of dentifrice and toothbrush container showing removable cover in the closed position.

Figure 4 is a cross sectional view of the dentifrice and toothbrush container on the line 4—4 in Figure 2.

Like reference numerals indicate corresponding parts throughout the drawing.

Referring to the accompanying drawing, the dentifrice and toothbrush container consists of the central hollow body member 10, the upper cover member 11 adapted to be removably secured to the upper edge 12 of the central body member 10 by any suitable means.

In the drawing the exterior surface of the upper edge 12 is double threaded to fit the interior double threaded portion of the lower interior edge 13 of the upper cover.

To the middle surface of the upper cover 12 is secured a clothes pocket or lining clip 14 enabling the entire container to be safely carried by the user on his or her person with maximum convenience.

Integrally attached to the upper inner wall 15 55 to be understood that many variations of use and

of the hollow body member 10 is the tooth brush 16 fitting inside the upper cover 11.

Secured to approximate centre of the exterior of the lower wall 17 which is perforated by a plurality of small apertures 18 is the slide member 19 adapted to be manually reciprocated within limits in order to permit the user to shake the powder 20 through the perforations 18.

In order effectually to prevent any powder accidentally falling into the user's pocket during transit and when the container is not in use the lower rounded edged cover 21 is movably secured by means of the pins 22 to the lower part of the hollow body member 10.

By reference to Figure 3 it will be seen that the lower rounded cover 21 has two projecting lugs 23 on the upper rim 24 each lug having an approximately central slot 25 adapted to receive the pins 22.

The structure of the lower movable cover 21 with its two lugs 23 and slots 25 when carried is shown in Figure 3 and when in use is as shown in Figure 1.

It will be noted that the slots 25 are set at a slight angle to the parallel edges of the lugs 23 in order that the cover may fit tightly on to the body 10.

In use as a dentifrice container the container is withdrawn from the clothes pocket, lining or handbag of the user and the upper cover 16 is detached from the body member 10.

The lower cover 21 is then slid from the position shown in Figure 3 to that shown in Figure 1, the slide member 19 is then pulled out to permit the powder being sprinkled on to the hand or other surface whence it is transferred easily to the brush member 16 for use.

It is obvious that the container and brush may be used for many purposes and that many variations of structure are possible.

It may be used for teeth cleaning and it may also be used where a powder having obnoxious characteristics is to be applied to another object as for example flux for soldering and various bases for paints and enamels.

It is also to be pointed out that the hollow chamber is admirably adapted to contain not merely various powders but also tubes containing various pastes as tooth pastes and the brush member, instead of being integral with the body 10 may be detached and loose within the upper cover.

Therefore although a preferred embodiment and use has been described and illustrated it is to be understood that many variations of use and

structure are possible without departing from the spirit and scope of the invention as covered by the appended claims.

What I claim is:

1. In a container a shank member, said shank member having a hollow chamber therein adapted to contain dischargeable material, said chamber having a perforated base for discharging the material therethrough, a slideable closure plate to control discharge of said material through said perforations, a cover member telescopically engageable over the end of said shank to enclose said closure plate, said cover being slideable to engage or disengage it from the shank and being secured in slideable captive relation to the shank, said cover being swingable out of the axial line of said container, when disengaged therefrom clearly to expose said closure plate, a brush member integral with said shank member at its opposite end, the said hollow shank member forming a handle for said brush member and a cover member removably secured to said opposite end of said shank to enclose said brush.

2. In a container a shank member having a

5 hollow chamber therein provided with a discharge outlet in its lower end and a closure plate controlling said discharge outlet, a cap member designed telescopically to engage said lower end to enclose said closure plate, said cap member having a base and a peripheral wall at right angles to the base to telescope over said shank, a pair of spaced apart parallel lugs projecting from the peripheral wall of the cap member said lugs having coinciding slots therein disposed at an angle to the longitudinal axial line of said lugs, said shank having opposed pins projecting toward the wall of the chamber at the lower end of the shank receivable in said slots to retain said cap member in slideable captive relation with the shank, said cap being slideable telescopically to engage and enclose the lower end of said shank, said angular slots forming with said pins means for tightening said cover on said shank, said cap member when slid from engagement with said shank being swingable out of the axial line of said container clearly to expose the closure plate.

PERCY GORDON WATT.
